The Majestic Company, Huntington, Ind., a
corporation

Application March 27, 1941, Serial No. 385,445

3 Claims. (Cl. 126—288)

This invention relates to a fireplace damper control.

The chief object of the present invention is to simplify the construction as well as the installation of a fireplace damper structure and to increase the efficiency of operation of such damper control.

The chief feature of the invention consists in the support for the damper and the operating element connected thereto and especially the support for the latter element, its association with the latter element and its support by the damper structure proper.

Another feature of the invention consists in the construction of a support arrangement and its support by the damper construction.

Other objects and features of the invention will be set forth more fully hereinafter.

The full nature of the invention will be understood from the accompanying drawings and the following description and claims:

In the drawing, Fig. 1 is a top plan view of the damper construction.

Fig. 2 is a bottom plan view thereof.

Fig. 3 is a transverse sectional view taken on line 3—3 of Fig. 2 and in the direction of the arrows, the parts being shown in the full open position, the dash lines diagrammatically indicating an intermediate position and the dash line indicating the full closed position of the operating element.

In the drawing, the numeral 10 indicates a back plate, 11 the front plate and 12 the side plates of the damper base structure. Extending upwardly from each of the portions 12 are the side plates 13. Extending upwardly from the forward edge of the rear plate portion 10 is the portion 14. Extending upwardly and rearwardly from the rear edge of the front plate portion 11 is the portion 15. The plate portion 14 is provided with an opening 16 adapted to be closed by a damper plate.

Adjacent each side edge of this opening, it will be noted that the walls are inwardly directed at the lower portion forming a plate bearing ledge 17. Adjacent the lower end of said ledge and rising upwardly and rearwardly is the flange 18. At least one of said flanges is apertured as at 19. Adjacent but slightly spaced from these ledges and extending upwardly from the portion 14 are the abutments and stops 20.

The groove 21 in effect defined by the lower portion of the portion 14 adjacent the opening 16 and the forward lower portion of the abutments 20 constitutes a fulcrum bearing for the

lower edge 22 of the damper plate 23. This damper plate may be of boiler plate character. The several edges about the opening 16 may be suitably faced by machining, grinding, or the like, to form a flat plane bearing for the forward and lower face of the damper plate.

Suitably secured to the underface of this damper plate 23 is a bracket 24 provided with spaced ears 25. Extending across these spaced ears is a member 26 which may be of suitable character but provides a pivotal support for the free end of the operating element 27. This operating element is herein illustrated as a casting and has its free end 28 flattened in what might be termed a vertical direction and apertured for connection with the member 26.

The entire midportion of this member 27 is laterally enlarged as at 29 and this enlargement includes an opening 30 therein. This opening is defined by an annular boss arrangement 31 on its forward face. Extending angularly thereto from the operating arm portion 32 and the latter is enlarged laterally as at 33 and apertured as at 34. This apertured portion 33 normally is positioned at an angle so that when the damper construction is properly mounted in the fireplace, the plane of the portion 33 is inclined to the front face of the fireplace and is inclined to a vertical plane transverse to the said front face of the fireplace. This angularly positioned end 33, therefore, is exposed in the fireplace opening and is so exposed that the aperture 34 is visible so that an angle poker, or the like, can be readily applied to it for operation or movement of the member 27—32. The front plate 11 at its upper outer edge is provided with an upwardly extending boss 40 which forms a groove 41 in the lower face.

On the lower face there is provided a similar but oppositely directed boss 42 grooved as at 43. The plate portion 11 between the two bosses is relieved or cut away as at 44 and there thus is provided an over and under bearing arrangement, having a common axis. Axially aligned with said bearing and on the underside of the back plate 10, is the boss 45 having the groove 46 in its upper face, this groove being axially aligned with the before mentioned forward bearing. The rear wall 14 adjacent its junction with the portion 10 is apertured as at 47. This completes the bearing arrangements at the front and rear of the damper structure channel.

The support for the operating member 27—32 now will be set forth and the opposite ends thereof are mounted in the longitudinally aligned

bearing arrangements. This support is of two-piece character. The main piece is elongated and includes a reduced free end 48 axially slideable in the rearward bearing. The member is extended across the damper plate closed channel, as shown, and includes the portion 49, the conical portion 50 grooved as at 51, another conical portion 52 and a cylindrical portion 53.

The conical portion 52 has a maximum cross section less than the maximum cross section of the conical portion 50. The cross section of the grooved portion is approximately that of the maximum cross section of the conical portion 52. The portion 53 is somewhat elongated and is centrally apertured as at 54. Slidably supported thereby and therein is a rod member 55. This rod member is provided with a transverse opening 56 and secured therein is a cotter key or like, 57.

The stop bar structure including the several portions 48 to 57, inclusive, may be mounted as follows: The end 48 is inserted in the rearward bearing in the plate 11 as far as it will go, then having previously inserted the rod member 55 in the recess or aperture 54 of the portion 53 as far as it can be seated, the stop bar structure is elevated until its axis is aligned with the aligned bearings. Then the rod 55 is extended until the opening 56 therethrough is exposed. When this occurs the rod is supported by the downwardly directed bearing portion 42. Then the cotter key or other locking means 57 is applied to the aperture 56 and the stop bar structure is properly mounted.

Previous thereto, naturally the operating arm has been mounted on the stop bar structure, as shown clearly by the full, dotted and dash lines. When the operating bar is at its maximum forward position, the boss 31 bears on the portion 53, and the damper plate is closed, being held closed by gravity acting upon said damper plate and the operating arm. When the operating arm is positioned so that the boss 31 engages the shoulder immediately adjacent the enlargement 52, the damper plate is held in half open position through gravity acting on the plate and the operating arm. When the operating arm is positioned so that it is seated in the groove 51 of the conical portion 50, the damper plate structure is locked in the wide open position. It will be readily apparent that an angle poker applied to the aperture 34 of the portion 33 and manipulated back and forth can readily adjust the operating element to the proper position.

Herein it will be noted that the damper plate 23 is cut away on at least one side edge 60 as indicated at 61, leaving adjacent its lower edge and at the side a projecting portion 62. This projecting portion can be seated in the aperture 19 and thus constitute an additional pivotal element for the damper body portion and damper plate connection. If desired the opposite side of the damper plate may be similarly cut away and the opposite ledge or flange portion 18 may be similarly apertured. However, one of these supports has been found sufficient.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a fireplace damper construction having a channeled damper throat forming body portion and a damper, said body portion pivotally supporting the damper for the control of the channel through the body portion, the combination of an axially extensible structure extending completely across the channel and comparatively stationary mounted at the opposite ends upon the channel throat forming body portion and solely by the latter, a member selectively positionable upon the structure and retained thereby for damper control and having one end connected to said damper for control thereof and the other end free and extending downwardly below the body portion for manual actuation of said member and damper from the fireplace opening, the extensible structure and member having portions permitting displacement therebetween longitudinally of the structure and preventing material lateral displacement therebetween, inwardly directed flange means at opposite sides of the opening at the upper end of the channel in the body portion and constituting stops for limiting damper closing movement, an apertured means projecting upwardly at the side of the opening, the damper being of substantially plate type and recessed at a side edge adjacent the projecting means for clearing the latter when closed, the portion below the recess forming a pintle seatable in the projecting means aperture for damper pivoting.

2. In a fireplace damper construction including a channeled, throat-forming body portion with a damper controllable outlet opening therethrough, and damper position controlling means including an axially extensible cross-bar structure, the combination of aligned bearings integral with the channeled body portion at the front and back thereof for cross-bar structure mounting therein from confronting ends of the bearings, one of said bearings including a grooved boss, the groove opening upwardly and the body portion adjacent the opening including an aperture aligned with the groove.

3. In a fireplace damper construction including a channeled, throat-forming body portion with a damper controllable outlet opening therethrough, and damper position controlling means including an axially extensible cross-bar structure, the combination of aligned bearings integral with the channeled body portion at the front and back thereof for cross-bar structure mounting therein from confronting ends of the bearings, one of said bearings including a pair of axially spaced, oppositely directed grooved bosses on the body portion, the grooves being aligned, the body portion therebetween including an opening therethrough, the grooves forming a spaced bearing arrangement.
